Attorney, Agent, or Firm—Mathew R. P. Perrone, Jr.

[57] CLAIM

The ornamental design for an L-shaped table, as shown and described.

DESCRIPTION

FIG. 1 is a front perspective view of an L-shaped table showing my new design;

FIG. 2 is a rear perspective view thereof;

FIG. 3 is a right side elevational view thereof;

FIG. 4 is a right end elevational view of FIG. 2;

FIG. 5 is a rear elevational view of FIG. 2;

FIG. 6 is a left side elevational view of FIG. 1;

FIG. 7 is a top plan view thereof;

FIG. 8 is a bottom plan view thereof;

FIG. 9 is a front perspective view of a second embodiment of an L-shaped table shown in FIG. 1;

FIG. 10 is a rear perspective view thereof;

FIG. 11 is a top plan view thereof;

FIG. 12 is a bottom plan view thereof;

FIG. 13 is a front perspective view of a third embodiment of an L-shaped table shown in FIG. 1;

FIG. 14 is a right side elevational view thereof;

FIG. 15 is a right end elevational view thereof;

FIG. 16 is a rear elevational view thereof; and,

FIG. 17 is a left side elevational view thereof.
